UNITED STATES PATENT OFFICE.

DAVID GEESNER, OF WORCESTER, MASSACHUSETTS.

CLOTH-TREATING MACHINE.

SPECIFICATION forming part of Letters Patent No. 744,744, dated November 24, 1903.

Application filed April 4, 1899. Serial No. 711,672. (No model.)

To all whom it may concern:

Be it known that I, DAVID GEESNER, a citizen of the United States, and a resident of Worcester, in the county of Worcester and 5 State of Massachusetts, have invented certain new and useful Improvements in Cloth-Treating Machines, of which the following is a specification.

In my Patent No. 387,288, of August 7, 1888, 10 I have described a process which consists of pressing the cloth and then moistening and steaming it while it is held under pressure by pressing the same in contact with the moistening apron or jacket between two heated surfaces, and in my Patent No. 387,287 I have 15 described a construction or machine by which this process may be carried out. In that machine the cloth first receives a dry pressure between two heated and dry pressing-surfaces and next undergoes a moist pressure. 20 In this first pressing process between the dry pressing-surfaces one of the surfaces is a stationary bed-plate, and the other is a traveling heated cylinder carrying the cloth, so that the cloth undergoes a certain amount of 25 friction or stretch during the first pressing, which is incidental to all rotary pressing when no apron is used. The cloth pressed upon such a machine is finished satisfactorily to 30 the mills; but when this same cloth reaches the trade, who make it up into suits, it has to be shrunk sufficiently to take up all the stretch caused by the first dry pressing against the stationary pressing-bed. On 35 light-weight goods, which are of sleazy, flimsy character, with little body to them, this stretch amounts to more than it does on heavy-weight goods, which have more body, and I therefore construct the machine described in my 40 Patent No. 565,072 with a view of pressing these lighter materials without in any way stretching them in the pressing process, because the endless apron over which the cloth passes in that machine sustains the friction 45 and pull produced by the stationary bed-plate underneath. In that machine of Patent No. 565,072, therefore, the stretching of the cloth incident to the ordinary rotary press is done away with, and it is therefore 50 on many classes of goods a better machine to use and on some classes the only rotary machine that can be used.

When goods are pressed and finished in the mills either on an ordinary rotary press or on an apron-press, as described in my Patent No. 55 565,072, the mills prefer not to steam the goods very much after pressing, for fear of removing too much of the finish imparted by those machines, because those goods have to pass through several hands before reaching 60 the clothier who cuts the cloth up into suits, and consequently have to stand a good deal of handling in the meantime. Therefore the mills prefer to impart a dry hard pressing to insure a firm handle of the cloth for some 65 time to come, and it is customary to leave it to the clothier to either do the final sponging or steaming himself or have it done by one of the many establishments in operation for that purpose in all of our big manufacturing cities. These spongers do not press 70 the cloth or finish it at all. They simply roll the cloth fairly loose upon a perforated copper roll, winding it thereupon spirally, and blow steam through it until it has penetrated the 75 fabric thoroughly all over. This steaming process as carried out by the spongers to thoroughly shrink the cloth in both width and length at the same time removes the finish so laboriously imparted to the cloth by the mills, 80 and when applied to face goods in which the nap is supposed to lie smoothly in one direction this steaming raises the nap and roughs it up, giving the fabric an uncouth and raw appearance, which the clothiers are forever 85 objecting to. Constant complaint is made by the clothiers of this fact when the goods are returned to them from the spongers previous to cutting up into suits, as the goods lose too much in handle and appearance during this process of steaming or shrinking on the perforated copper roll, and the spongers are frequently asked to refinish the shrunk cloth, but in such a way that it shall not show 90 any water-marks when the tailor applies a hot iron and wet cloth to the goods subsequently. Some spongers, therefore, take the cloth after steaming upon the perforated rolls and next put it between cold plates and papers and give 95 this cloth a so-called "cold" press in order to return some sort of a press or finish; but if this press is put on too long or too severely or the cloth is still slightly warm when put in the cold press it will still produce a certain luster 100

which will show spots if water is afterward dropped upon it. Putting the cloth after sponging between cold plates and papers is, moreover, a costly process, as it takes lots of time to fold the goods, and as the cloth has to remain in such press for half a day or more a sponging establishment would be required to have a great many of these cold presses on hand to do much refinishing.

10 To enable the spongers to refinish their cloth after steam-shrinking it, I have made the improvement shown and described in this application.

15 In the accompanying drawings, Figure 1 is an elevation of one end of the machine. Fig. 2 is a horizontal section on the line A B of Fig. 1, and Fig. 3 is a vertical section on the line C D of Fig. 1.

20 The following description is to be read in connection with the specification of my said Patent No. 565,072.

25 The following description of the supports at one end of the machine will suffice for both ends, since the supports at the opposite end are the same.

25 a is an end frame fastened to one end of a base-plate b.

30 c is a bracket extending rearwardly from the frame, upon which the rolling and folding apparatuses for the cloth are mounted. d is another bracket resting on top of the end frames a near the rear, facing upwardly and carrying on its top sliding frame e, carrying a pair of rollers f and g, with a trough h placed under one of them.

35 i is the main or pressing cylinder, and l is its bed-plate, which can be moved vertically up and down, being guided in this direction by fork-guides m. At n the bed-plate is 40 shackled to links n', which have screw-threaded connections p to unite them with the shackles o, which at q are pivotally connected to carriages r, that move in slides of the frames a, so that when the shaft 23 is 45 turned so as to bring the cam t into the position shown in the drawings it will force (through pillow-blocks u) the carriages r upward, bringing the bed-plate l into a pressing position. The manner in which the shaft 50 23 is operated need not be reiterated here, as it has been fully described in my Patent No. 565,071 of the same date, August 4, 1896, which was pending at the same time as my Patent No. 565,072, above referred to.

55 v is an endless apron passing between the cylinder i and the bed-plate l over the cylinder w in the direction of the arrows, the cylinder w being driven from the main cylinder i, as shown in my Patent No. 565,071.

60 x is a swivel-roller on the outside of the apron running in the bracket y, which is pivoted at z in its middle and at the middle of the under side of the gird a', so as to act as an automatic regulator to insure the apron 65 v to run straight. 1 is another roller mounted upon a carriage 2, which slides upon ways 3 on a bracket 4 and is operated by a hand-

wheel 5, so as to serve as a take-up for the slack of the apron, which in the course of time is produced by the friction exerted upon 70 the inner side of the apron between it and the bed-plate l.

6 6 is another endless seamless apron which runs around the pressing-cylinder i and the roller g, which is mounted on top of the sliding frames e in detachable fixed bearings 7.

75 Pressed against the apron 6 from below is the roller g, having its bearings in the lever 8, which is fulcrumed on the sliding frame e at 9 and is adjusted vertically by the hand-wheel 10, screw-threaded upon the spindle 11, pivotally connected to the elongation e' of the sliding frame e.

80 The frame e is moved toward and from the cylinder upon its guides by a threaded rod d', carried by the bracket 85 d and engaging a nut or projection e'', secured to the frame e by the set-screw e'. The outer end of said threaded rod carries the worm-wheel 14.

85 If a wrench be applied to the square of the spindle 12, which carries 90 a worm 13, which meshes into the worm-wheel 14, the sliding frame e can be moved horizontally toward or away from the cylinder i, and thus the apron 6 can be slackened or kept taut at will. The lower part of the 95 roller g will be immersed in water contained in the trough h, and the water taken up by the roller g will be transferred to the apron 6, so as to wet the same. By turning the hand-wheel 10 so as to force the lever 8 downward at that end the roller g will be pressed 100 upward against the roller f, and the water carried up by the roller g and communicated to the apron 6 will be squeezed out of the same to a greater or less degree, as the operator may see fit, leaving the apron 6 merely damp, with the superfluous water all wrung out of it, when in its travel it comes forward into contact with the cloth 15, which passes between this apron 6 and the apron v, that 110 travels over the bed-plate.

110 16 is an open steaming device attached to the frame a, which is adapted to thoroughly shrink the cloth in both length and width.

115 24 is a radiator consisting of a coil of steam-pipes that may be heated either directly by a supply of fresh steam or by the exhaust-steam that has passed through the cylinder i and the bed-plate l. The object of this radiator is to keep the apron v dry in case it should 120 when handling very light fabrics become moistened by the steam generated by the heated pressing-cylinder i pressing against the wet apron 6. This apron v even when 125 pressing somewhat heavier goods would nevertheless absorb some of the moisture from the wet apron 6 beyond the edges of the cloth, which at all times would be several inches narrower than either the apron 6 or apron v, so that there would be nothing to prevent these 130 aprons being pressed together whenever there was no cloth between. Keeping the apron v thus dry at all times will give that side of the cloth which lies next to it a very much higher

finish and likewise drier finish than the upper side of the cloth receives which lies next to the wet apron 6 in pressing.

18 and 19 are respectively a cloth-roll and a folder, which may be constructed and operated in any suitable manner.

The operation is as follows: Before refinishing the cloth upon this machine it may be either rolled upon a perforated copper cylinder and thoroughly steamed in that condition, as heretofore, or the shrink may be taken out of the cloth by leading it through an open steaming device, as 16, for instance, attached to the frames *a* of my machine, which will thoroughly shrink the cloth in both length and width, and then the cloth may receive another pressing between the apron *v* above the bed-plate *l* and the wet apron 6 around the steam-heated cylinder *i*, the nap of the fabric after being steamed being smoothed down again or laid by the brush 17 immediately before the cloth enters between the dry and wet pressing-surfaces of my machine. By using an endless moist water-absorbing apron like 6 and wetting it thoroughly with ordinary cold water and then uniformly squeezing the water out of it, as shown in this machine, this apron can be kept more moist than if steam only were applied to it instead of water. When the cloth leaves the machine, the nap will not only be laid and the luster and the face be made waterproof, but another pressing is imparted to it by the pressure from the bed-plate against the dry apron *v* from underneath, so that the cloth resumes after having been shrunk a firmness of handle approaching in character and in many cases being equal to that imparted by the mills. The cloth after passing between the dry and wet aprons *v* and 6 will pass over the roller 18 through the folder 19 to be folded upon the floor or to be rolled up upon a beam 20 on top of the roller 18.

I claim—

1. In a rotary cloth-press in combination a cylinder, a presser, two aprons running between the same, and a combined apron take-

up and moistening device, substantially as described.

2. In a rotary cloth-press in combination, a cylinder, a presser, two aprons running between the same, apron-moistening apparatus and means whereby the same may be adjusted for different degrees of moistening, substantially as described. 50

3. In a rotary cloth-press, in combination, a cylinder, a presser, two absorbent aprons running between the same, means whereby the cloth is guided between said aprons, means whereby one of said aprons is moistened and 60 means whereby the other of said aprons is dried; both said moistening and drying means being other than the presser or cylinder; whereby the cloth is pressed between two aprons one of which is maintained moist and 65 the other maintained dry.

4. In a cloth-treating machine, the combination of cloth-pressing devices, an apron passing between said pressing devices and a combined apron take-up and moistening device. 70

5. In a rotary cloth-press in combination, a cylinder, a presser, two aprons running between the same, a combined apron take-up and moistening device, and means for adjusting the moistening device for different degrees of moistening. 75

6. In a rotary cloth-press in combination a cylinder, a presser, two absorbent aprons running between the same, means whereby the apron running in contact with the presser is dried, means whereby the other apron is moistened, and means whereby the cloth is guided in contact with said moistened apron; both said moistening and drying means being other than the presser or cylinder whereby the cloth and the wet apron are pressed together between the dry apron and the cylinder. 85

DAVID GESSNER.
